UNITED STATES PATENT OFFICE.

ALBERT N. EATON, OF OMAHA, NEBRASKA.

DESIGN FOR A FEED-TROUGH.

57,620.

Specification for Design.

Patented Apr. 26, 1921.

Application filed September 18, 1920. Serial No. 411,328. Term of patent 14 years.

To all whom it may concern:

Be it known that I, ALBERT N. EATON, a citizen of the United States, residing at Omaha, in the county of Douglas and State of Nebraska, have invented a new, original, and ornamental Design for a Feed-Trough, of which the following is a specification, reference being had to the accompanying drawing, forming a part thereof.

Figure 1 is a plan view of a feed trough, showing my new design. Fig. 2 is a side view of the same. Fig. 3 is an end view of

the feed trough. Fig. 4 is a view of the feed trough in longitudinal section.

I claim:

The ornamental design for a feed trough, as shown.

In testimony whereof, I have affixed my signature in presence of two witnesses.

ALBERT N. EATON.
